Primary Examiner — Jeffrey D Asch(74) *Attorney, Agent, or Firm* — Sutherland Asbill & Brennan LLP(57) **CLAIM**

The ornamental design for a mobile communications device with handle members, as shown and described.

DESCRIPTION

FIG. 1 is a perspective view of a mobile communications device with handle members showing my new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof; and,

FIG. 8 is a perspective view thereof showing a different orientation of the handle members relative to the remainder of the mobile communication device.

The broken lines showing the hinge in FIGS. 5 and 7 and the broken lines around the outer periphery of the inside surfaces in FIGS. 1, 4, 6, and 8 represent the bounds of the claimed design, while all other broken lines are directed to environment and are for illustrative purposes only; the broken lines form no part of the claimed design.
